UNITED STATES PATENT OFFICE

2,642,065

ODONTALGIC DEVICE

Mario Negri, Rome, Italy, assignor to Ditta A. Gazzoni & Co., Bologna, Italy

Application April 9, 1951, Serial No. 219,977
In Italy April 15, 1950

3 Claims. (Cl. 128—269)

1

The present invention relates to a device for bringing in contact with the internal surface of the external auditory meatus an analgesic fluid for acting on the innervation of the trigeminal nerve.

According to the invention a vial containing the analgesic fluid is inserted in a protecting container having a substantially frusto-conical shape and from the end corresponding to the minor basis of the frusto-cone there projects an absorbent element used to spread the fluid inside the auditory meatus.

The larger part of the frusto-cone extends in a substantially cylindrical element surrounding the vial and protecting it. This element is provided with external threads on which can be secured a cap-element having internally a breakable needle-shaped projection. When the cap is screwed on, the glass vial, owing to the pressure exerted by the tip of said projection on the surface of the vial will break. The pressure can reach a high value, without requiring a great force, owing to the action of the inclined plane of the thread.

The cap may be extended by a handle to facilitate the screwing.

Two preferred forms of embodiment of this invention are shown in the enclosed drawings, wherein:

Fig. 1 shows an elevational view of the device with the cap on;

Fig. 2 shows a central vertical cross-section of Fig. 1;

Fig. 3 shows a view of a different form of embodiment of the container and;

Fig. 4 shows the central vertical cross-section of the container of Fig. 3.

With reference to the drawing:

The form of embodiment shown in Figs. 1 and 2 comprises a frusto-conical rigid container 1, reinforced by ribs 2. The container has at one end a cylindrical portion 5 with threads 6, on which the cap 7 may be screwed.

Inside the container 1, absorbent material 8 is placed, formed for instance by wadding, a part of which is wrapped in a covering 4 made of a sheet of gauze, and projects from the end 3 of the container. A vial 9, containing the analgesic fluid, and provided with a rod 16 is arranged in the container and rests on the wadding, while the rod 16 penetrates into the wadding 8.

The cap 7, the lateral part of which is threaded at 10 engaging with threads 6 of the cylindrical part 5, is internally provided, in a central posi-

2

tion, with a needle-shaped projection 11, and around this latter with a cylindrical flange 12 which surrounds the vial containing the analgesic. When the cap 7 is screwed on the cylindrical part of the container 1, the needle 11 causes the breaking of the vial 9, while the part 12 which, owing to the descent of the cap 7, surrounds the vial 9, prevents the dissipation of the fluid outside the container.

10 The wadding 8 then absorbs the analgesic fluid which through the projecting part 17 comes out from the container and, owing to the sharpened frusto-conical shape of the element 1, can be spread in the most internal part of the external auditory meatus, in order to obtain the best way the therapeutic efficacy of the employed product.

20 The protecting container according to the invention permits easy transportation and easy conservation of the odontalgic device.

As the spherical form for the vial containing the analgesic fluid is the form having maximum resistance it requires considerable stress for its breaking. Figs. 3 and 4 illustrate a different form of embodiment, wherein this stress may be more easily exerted.

30 In this case, the part 13 is substantially the same as the corresponding part described in the preceding embodiment, but the upper part 14, instead of ending with a plane surface, so that all the screwing stress for breaking the analgesic vial may be concentrated on its cylindrical lateral part, has a projection 15, substantially of a conical shape, allowing the cover to be more easily gripped.

35 The device has been shown in Figs. 3 and 4 without the absorbent element and the vial which are identical in both cases.

I claim:

40 1. A device for bringing in contact with the internal surface of the external auditive canal an analgesic fluid intended to act on the innervation of the trigeminal nerve, comprising in combination a container provided at one end with a cap and at the other end with an opening, an absorbent material in said container and partially projecting from the opening of said container, a covering of absorbent material wrapping said projecting part of said absorbent material, a vial containing the analgesic fluid in said container resting on the absorbent material, and means in said cap of the container adapted to break said vial.

45 2. A device for bringing in contact with the internal surface of the external auditive canal an

analgesic fluid intended to act on the innervation of the trigeminal nerve, comprising in combination a frusto conical container having at one end a cylindrical portion externally threaded and at the other end an opening, a cap adapted to be screwed on said cylindrical threaded portion, a pin integral with said cap and projecting inside said container, an absorbent material in said container and partially projecting through the opening thereof, a covering of absorbent material wrapping said projecting part of said absorbent material, a vial containing the analgesic fluid in said container on said absorbent material, a rod integral with said vial and projecting therefrom, said rod penetrating into the absorbent material, said vial being in contact with said pin, said pin being adapted to cause breaking of the vial when the cap is screwed on the cylindrical threaded portion of the container.

3. A device for bringing in contact with the internal surface of the external auditory canal an analgesic fluid intended to act on the innervation of the trigeminal nerve, comprising in combination a frusto conical container having at one end a cylindrical portion externally threaded and at the other end an opening, a cap adapted to be screwed on said cylindrical threaded portion, a pin integral with said cap and projecting inside the container, a cylindrical flange projecting from the cap and surrounding said pin spaced apart therefrom, an absorbent

material in said container and partially projecting from said opening of said container, a covering consisting of a sheet of absorbent material wrapping said projecting part of said absorbent material, said projecting part of the absorbent material and said covering being adapted to penetrate into the external auditory canal, a sealed vial containing the analgesic fluid arranged in said container on said absorbent material and adapted to partially penetrate in said cylindrical flange of the cap, a rod integral with the vial and projecting therefrom which penetrates into the absorbent material, said vial being in contact with said pin, said pin being adapted to cause the breaking of the vial when said cap is screwed on the cylindrical threaded portion of said container, whereby the analgesic fluid contained in the vial is absorbed by the absorbent material and the said covering when the projecting part of the absorbent material and the covering are introduced into the external auditory canal.
